UNITED STATES PATENT OFFICE.

ALFRED A. RUTTAN AND FREEMAN A. GILLICE, OF ROCHESTER, NEW YORK, ASSIGNEES
TO EASTMAN KODAK COMPANY, OF ROCHESTER, NEW YORK, A CORPORATION OF
NEW YORK.

COMPARTMENT CAN.

Application filed June 17, 1927. Serial No. 199,486.

This invention relates to cans or receptacles having two separate compartments in which various materials may be packed. One object of the invention is to provide a 5 two-compartment can which is made of simple easily formed parts. Another object of the invention is to provide a compartment can in which the can sections are frictionally held together independently of the 10 cover. Another object of the invention is to provide a two-compartment can in which each can has an opening facing towards the other can section and between which a single cover or cap may be placed. Another 15 object is to provide a two-compartment can in which a cap placed between the cans will be automatically retained in position by bringing the can sections into frictional engagement. Still another object of the 20 invention is to provide complementary flanged plates on each can which will frictionally hold the can sections together. And other objects will appear from the following specification, the novel features being particularly pointed out in the claims at the 25 end thereof.

Coming now to the drawings wherein like reference characters denote like parts throughout:

30 Fig. 1 is a half section half side elevation of a compartment can constructed in accordance with and illustrating a preferred form of our invention;

35 Fig. 2 is an enlarged detail section showing the can compartments in a different position from that shown in Fig. 1;

40 Fig. 3 is a perspective view of the can shown in Fig. 1.

In the illustrated embodiment of the invention the compartment can consists of two sections 1 and 2 which may be frictionally held together as will be hereinafter more fully described. Can section 1 preferably consists of a top wall 3 having a flanged edge 4 rolled over at 5 with the upper edge 6 of a cylindrical side wall 7. The side wall 7 is preferably folded back at 8 to form a reinforced bead around the bottom edge, and is then formed inwardly at 9. The annular wall 9 has a central opening 10 adapted to receive a cover 11 which is preferably flanged, as shown at 12.

Around the opening 10 there is a two-

walled flange 13 which serves to strengthen the opening which receives the can cover 11. 55 There is a second double walled flange 14 extending between the flange 10 and the outside of the can. This flange is adapted to frictionally engage a complementary double walled flange 15 which is formed in the annular member 16 which forms the top of can 2, wall 16 being preferably bent upon itself at 17 similar to the bend at 8 of can 1. The inside edge 18 which forms the periphery of the opening in the annular member 60 16 is preferably bent, as shown at 19, to reinforce or strengthen the metal and the depression formed by such bending is just sufficient to permit the flange 12 of cover 11 to lie between the can sections when the parts 70 are in the assembled relation shown in Fig. 1.

As illustrated in Fig. 2, if the cover member 11 should not be frictionally engaged in the opening 10 of the annular member 9 it is only necessary to force the can sections together bringing the complementary flanges into firm frictional contact and to draw the cover 11 firmly into the opening 10. In this way when the flanges 8 and 17 of the can sections are in contact the cover is likewise 80 securely seated.

Although we prefer to depend upon the frictional contact between the annular can walls 9 and 16, if desired an additional securing means such as a paster 20 may be 85 fastened about the joint 21 between the can sections to form an additional safeguard to prevent accidental displacement of the can sections.

The operation of filling the two-compartment container is simple. Compartment 1 may be loaded with the desired material and the cover 11 placed in the opening 10. After loading the desired material into compartment 2 through opening 18 the two containers may be forcibly brought together so that the outside walls of the annular flange 14 may frictionally engage the inside walls of the annular double walled flange 15 thus holding the sections together. 90

100 It should be noted that as there is considerable wall surface in the complementary flanges that the frictional holding power of this joint is sufficient to retain the can sections firmly together even where they are to 105 be comparatively roughly handled. It is im-

possible to remove the can cover 11 without first separating the can sections and this may be done by inserting a sharp instrument between the contacting flanges 8 and 17.

5 Having thus described our invention what we claim as new and desire to secure by Letters Patent is,—

10 1. In a two-compartment container the combination with two can sections, of an annular flanged plate on each can section, the flange on one can section being complementary in shape to the flange on the other can section whereby the two sections may be frictionally held together by the complementary flanges, and a cover adapted to lie between the two annular flanged plates, being adapted to frictionally engage in the opening and in one of the annular members.

15 2. In a two-compartment container the combination with two can sections, of annular flanged plates one on each can section, the flanges of one annular plate being complementary in shape to the flange on the other annular plate whereby the two sections may be frictionally held together, a cover adapted to lie between the two annular flanged plates, said cover being adapted to frictionally engage in the opening of one annular plate and to be held in the opening by the other annular plate when the two can sections have been brought into frictional engagement.

20 3. In a two-compartment container the

combination with two can sections, of an annular flanged plate on each can section, each 35 annular plate having a plurality of flanges, one of the flanges on each plate being similar in shape and the other flanges on the annular plates being of complementary shape whereby the two can sections may be frictionally held together by the last mentioned 40 complementary flanges, the first mentioned flanges on the annular plates being adapted to contact when the complementary flanges are in frictional engagement.

45 4. In a two-compartment container the combination with two can sections, of an annular flanged plate on each can section, each 50 annular plate having a plurality of flanges, one of the flanges on each plate being similar in shape and the other flanges on the annular plates being of complementary shape whereby the two can sections may be frictionally held together by the last mentioned 55 complementary flanges, the first mentioned flanges on the annular plates being adapted to contact when the complementary flanges are in frictional engagement, and a cover adapted to lie between the annular plates and to frictionally engage the opening in one plate 60 when the can sections are frictionally engaged.

Signed at Rochester, New York, this 10th day of June 1927.
